UNITED STATES PATENT OFFICE.

JULES ARMAND BLIN, OF PARIS, FRANCE.

METAL BEDSTEAD.

Application filed November 14, 1921. Serial No. 515,110.

To all whom it may concern:

Be it known that I, JULES ARMAND BLIN, a citizen of the French Republic, residing at Paris, France, have invented new and useful Improvements in Metal Bedsteads, of which the following is a specification.

This invention relates to metal bedsteads preferably of aluminum or its alloys, characterized by the method of construction of 10 the lower frame and the means provided for ensuring rigidity of said frame by tying and strengthening the two longitudinal members with the head and foot of the bed constituting the frame, one of these arrangements comprising rigid cross pieces and the 15 other comprising cables fitted with tensioning devices.

Two forms of construction for carrying the invention into effect, are shown, by way 20 of example, in the accompanying drawings:

Figure 1 is a plan of the complete arrangement having rigid cross pieces fitted in the lower frame of the bedstead; Figs. 2, 3 and 4 show to a larger scale in vertical section respectively on the lines A A, B B and C C of Fig. 1, the manner of constructing the lower frame of the bedstead and the cross pieces; Figs. 5 and 6 show perspective views of the outline of the central cross piece and 25 one of the assembly fittings for this cross piece on the frame. Figs. 7 and 8 show in perspective the outline of one of the intermediate cross pieces and an assembly fitting therefor; Fig. 9 shows diagrammatically a 30 modified construction wherein the arrangement consists of cables and tensioning devices.

As will be seen from Fig. 1 of the drawing, the lower frame of the bedstead is 40 formed of two longitudinal members *a* suitably connected together with the ends *a*¹ at head and foot. These longitudinal members consist of two sheets of metal so as to form, when joined together a rectangular 45 section having an external recess *a*² (Fig. 2) on which can be fitted an ornament *a*³.

The two members *a* are connected by a central cross member *b* consisting of two sheets of metal bent U shape and fitted one 50 upon the other (Fig. 3) so forming a square section. This cross piece terminates at each end in two vertical wings *b*¹ obtained by bending the external strip of the cross piece (Fig. 5).

On the members *a* are fitted two gussets or

housings *c* (Fig. 6) whose shape corresponds to that of the cross piece *b* and whose two lateral sides are bent inwards to form slideways *c*¹ for the reception of the wings *b*¹ of the cross piece. 60

The latter rests on the stops *c*² obtained by bending the lower part of each of the gussets *c*.

The rigidity of the frame is completed by 65 four intermediate cross pieces *d* disposed diagonally. Each of these consists of a metal sheet bent to form an inverted triangular section (Fig. 4) whose apex is extended by two vertical walls *d*¹ bearing against each other and also having two wings *d*² 70 (Fig. 7).

Triangular gussets *e* (Fig. 8) having, like the gussets *c*, slideways *e*¹ and stops *e*² are fixed on the one hand in the angles of a frame formed by the longitudinal members *a* and by the ends *a*¹ on each of the posts *f* of the bedstead and, on the other hand, on the middle part of the central cross piece *b* so that, when the wings *d*² of the intermediate members *d*, are engaged in the slides *e*¹ 80 of these gussets and the vertical parts *d*¹ resting on the stops *e*², the four cross pieces *d* form the diagonals of the frame. 75

It will be clear that this arrangement of a central cross piece connecting the longitudinal members and four intermediate 85 diagonal members, gives an arrangement which ensures the rigidity of the lower frame by reason of the construction of these cross pieces of light metal such as aluminium 90 or its alloys and arranged so that they themselves have great strength.

This arrangement further provides a great advantage of being able to assemble or dismantle the parts easily and very quickly 95 without the necessity of any special tools and when dismantled, the constituent parts take up little room which therefore facilitates transport, packing and storage.

According to the construction shown in 100 Fig. 9 the arrangement comprises, as in the preceding case, a central cross member *b* connecting the two longitudinal members *a*. In the central part and on each of the side members of this cross piece are fitted clips or brackets *g*, *g*¹ carrying the axles for pulleys *h*, *h*¹ around which pass metal cables *i*, *i*¹ 105 fitted with tensioning devices *j*, *j*¹. These cables are attached at each end to ears *k*, *k*¹ secured in any convenient manner in the 110

angles formed between the longitudinal members a and the head and foot members a^1 forming the lower frame of the bedstead.

It is sufficient to give a few turns to the tensioning devices j, j^1 to obtain the necessary tension of the cables i, i^1 which are arranged in the diagonal lines of the frame so that they ensure in combination with the central cross piece, the rigidity of the whole.

10 I claim:

1. In a metal bedstead the combination with embossed head and foot plates, of side rails and a cross-bar for the side rails all constituted of two channelled members fit-

ting into one another, lateral wings at each 15 end of the said cross-bar, and gussets projecting from the inner sides of the side rails to receive said wings.

2. In a metal bedstead, a frame, a cross-tie in the frame, and four diagonal stays 20 each formed of a single metal strip bent to have a triangular section and wings at each end of the stay, and gussets fixed to the cross-tie and the end plates respectively to receive the wings of said diagonal stays and 25 impart rigidity to the frame.

JULES ARMAND BLIN.
